UNITED STATES PATENT OFFICE.

SILAS B. HAVENS, OF PAWTUCKET, RHODE ISLAND.

GAS-HEATING APPARATUS.

SPECIFICATION forming part of Letters Patent No. 443,829, dated December 30, 1890.

Application filed December 5, 1889. Serial No. 332,654. (Model.)

To all whom it may concern:

Be it known that I, SILAS B. HAVENS, of Pawtucket, in the county of Providence and State of Rhode Island, have invented certain new and useful Improvements in Gas-Heating Apparatus; and I do hereby declare that the following is a full, clear, and exact description thereof, reference being had to the accompanying drawings, and to the letters of reference marked thereon, which form a part of this specification.

This invention relates to that class of heaters for warming rooms, &c., in which gas is used for fuel; and its object is to produce an apparatus of that class that will be effective, ornamental, and light enough to be used in immediate connection with the arm of a chandelier or a gas side bracket by being placed over or around the burner in its usual position.

It is fully illustrated in the accompanying drawings.

Figure 1 shows an elevation of the heater in the position in which it is to be used on an arm of a chandelier or bracket with a gas-burner. Fig. 2 is a vertical section taken down through the center of the heater, showing the position of the burner and the deflector.

The body of the heater A is made of sheet metal or of other material that will stand a high heat without being injured. The lower half or portion of it is made of a fluted cylindrical shape, (see Fig. 1,) and the upper part is composed of a series of conical rings b, attached to vertical strips of material extending up from the fluted portion of the heater to the ring at the top. These conical rings are placed one above another, so as to leave an annular opening between the flaring lower edge of one ring and the contracted upper edge of the ring next below it.

The bottom of the heater may be left open or made partially closed, according to the area of the annular spaces left between the rings above, that the space for admission of air may be properly proportioned to the space provided for its exit after being expanded by heating in passing through the chamber. The top consists of a cover c, made with an edge slightly turned down to keep

it in place, and left loose, so that it can be turned around or taken off, if desired. A flat circular plate d, made rather smaller than the head of the heater, has a rod or wire a attached to its center, by which it is suspended from the top of the heater in the center, and may be held in a horizontal position, as shown, or inclined by bending the wire a slightly so as to take the position shown by the dotted lines in Fig. 2. This plate d serves the purpose of a guard or deflector to turn the current of heated air out through the annular openings in the sides of the heater and keep it from coming in contact with the top. It may be set at an angle, as shown in the dotted lines e e, Fig. 2, so as to throw the current of heated air toward the outlets on any side of the heater to the exclusion of the other side by turning the top of the chamber to which it is attached around, as above stated, which in some cases is necessary, as when the apparatus is used on a gas-bracket at the side of a room or near a mirror where the hot air, if allowed to pass out that side might injure the appearance of the walls or the frame of the mirror. The deflector d, after being set at an angle, as in Fig. 2, can be brought to face any side of the heater by turning the top to which it is attached around in its place.

The apparatus is supported on a wire framework g, that has a ring in its center to pass over the socket of the burner, and may be held in place by screwing the burner down on the ring.

The operation will be easily understood by referring to the drawings. B is the arm of a chandelier or bracket. The burner f is unscrewed, and the ring in the center of the wire frame-work g is placed on the screw-socket where the burner was, and the burner replaced and screwed down firmly into the ring in the frame. The heater A is then placed on the frame g and the gas turned on at the cock j and lighted. A draft of air is produced by the heat of the burner, which passes in through the bottom in the direction of the arrows o o and thence up out through the annular openings between the rings in the direction of the arrows s s, being heated to a high degree in passing through the

heater both by the gas-flame and the metallic sides of the heater and deflector.

The shape of the body of the heater can be largely varied to make it ornamental and 5 suit the taste of the user without departing from the principle of the invention.

One great advantage of this heater is that it can be used where there is not sufficient floor-space available for a heater of any of 10 the usual kinds and its perfect security with regard to children, as it is out of the way of every one and delivers its heat from above downward.

Having thus described my improvement,

what I claim as my invention, and desire to 15 protect by Letters Patent, is—

As a new article of manufacture, a heater for warming rooms, &c., consisting of a chamber having an opening below for the admission of air and openings in its sides above for 20 its exit, in combination with the deflector *d*, and provided with a frame-work to hold it on the arm of a chandelier, bracket, or suspension-rod, substantially as set forth.

SILAS B. HAVENS.
